CAN FEEDING MECHANISM

Nelis P. Bach, Geneva, N. Y., assignor to American Can Company, New York, N. Y., a corporation of New Jersey

Application November 2, 1932, Serial No. 640,805

6 Claims. (Cl. 198—22)

The present invention relates in general to can feeding mechanism and has more particular reference to the retardation of cans as they are received from a high speed operating machine so that the cans may be further handled without fear of denting or improper crowding.

In performing certain operations on tin cans the tendency of recent years has been to increase the speed of operation of certain machines such, for example, as double seamers which apply the bottom end to the can body or to can closing machines for double seaming the top end to the filled can, and such seaming machines often handle as many as three hundred cans a minute. Cans which are discharged from a machine at this speed are necessarily subjected to relatively rough handling unless special precautions are taken to properly catch them. They are liable in being guided around between guide rails to become dented or bent as a result of such excessively high speed.

The present invention contemplates slowing down of the cans and as they are reduced in speed they necessarily are brought closer together. In other words the spaced relation between adjacent cans as received from the high speed operating machine is reduced and the cans are brought into closer spaced relation.

The principal object of the present invention is the provision of a can feeding mechanism for receiving cans from a high speed operating machine and for gently retarding their travel so that they may be easily handled for subsequent operations in other machines or as is usual in filled and sealed cans coming from a closing machine so that they may be stacked prior to heat retorting or other treatment.

An important object of the invention is the provision of can receiving arms in a machine of the character described which individually receive the cans from the fast moving machine parts and, while permitting the cans to travel in a smooth, unbroken, straight or gradually curved line, gently retard their movement so that when they are delivered from the arms they will be traveling at a greatly reduced speed.

A further important object of the invention is the provision of a can feeding mechanism which receives cans in a given spaced relation and which brings them into closer spaced relation while retarding their travel.

Numerous other objects and advantages of the invention will be apparent as it is better understood from the following description, which, taken in connection with the accompanying

drawings, discloses a preferred embodiment thereof.

Referring to the drawings:

Figure 1 is a fragmentary plan view of the feeding mechanism embodying the present invention showing its relation to a movable high speed can carrier, parts being broken away;

Fig. 2 is a transverse sectional view taken substantially along the broken line 2—2 of Fig. 1; and

Fig. 3 is a fragmentary perspective view of one of the can receiving arms illustrating its retarding control.

The apparatus illustrating the present invention may be applied as an attachment to a can closing machine for filled cans or to a can double seamer for securing the bottoms to can bodies and is so positioned as to receive the cans as they are discharged from the fast moving part of the high speed machine.

This can feeding mechanism comprises a plurality of radially disposed turret arms pivotally carried on a uniformly rotating turret, each arm being cam controlled to move it on its pivotal connection with the turret so that after receiving a can and while it is being carried bodily forward with the turret the can engaging part is retrograded, retarded or moved backward by the pivoting of the turret arm. This control of the can travel is assisted by a suitably curved guide rail which holds the can in the pocket of the turret arm and gently guides it without abrupt change of travel until it is discharged in the ultimate place of deposit.

Only the discharging part of the high speed mechanism is illustrated in the drawings, this being indicated by a movable disc carrier 21 (Fig. 1) mounted on a shaft 22. These parts are suitably associated with a table 23 which is preferably a part of the seaming machine and which provides a floor for the moving can.

The carrier 21 is formed with spaced can pockets 24 into which seamed cans 25 are delivered in the usual manner. While in these pockets the cans are conveyed at a high rate of travel along a circular path determined by a guide rail 26 carried on a bracket 27 mounted on the table 23.

As a can 25 approaches the end of the guide rail 26 a turret arm 31 is brought into position to receive it, this arm being provided with a can receiving pocket 32. This pocket is moved opposite to the pocket 24 and at the same rate of lineal travel so that the can after leaving

the guide rail 26 is, for a moment, within both pockets 24, 32 of the members 21, 31.

The turret arm 31 is formed with a depending shank 35 (Figs. 2 and 3) which is carried in a vertical bore 36 formed in a turret 37. In the drawings there are illustrated four arms 31, all of which are carried on the turret 37, the shanks 35 being equally spaced from each other and at the same distance from the turret center. 10 Each shank is freely pivotally movable within its bore 36.

The turret 37 is keyed to a sleeve 41 of a gear 42 which is rotatably mounted upon a stationary shaft 43 carried in a bearing 44 formed in a housing 45. This housing 45 may be a part of the frame of the double seamer or it may be an independent unit. In the drawings it is illustrated as supporting a cover plate 46 on which the table 23 may be mounted. The turret 37 is formed with an annular groove 47 into which a part of the plate 46 loosely projects, this construction preventing entrance of moisture or extraneous substances within the gear housing during cleaning of the machine. The upper end 25 of the shaft 43 is reduced at 48 and is held in a bracket 49 bolted at 51 to the housing 45.

The gear 42 meshes with a pinion 52 which is keyed to the upper end of a vertical shaft 53 mounted in bearings 54 formed in the housing 30 45. The shaft 53 also carries a gear 56 which meshes with a gear 57 keyed to a vertical shaft 58 journaled in a bearing 59 formed in the housing. The shaft 58 may be any suitable drive shaft for the retarding mechanism and may or 35 may not be a part of the driving mechanism of the seaming machine.

The lower end of the shaft 53 is reduced where it passes through the gear 56 and a washer 61 and lock bolt 62 threadedly engaging the end 40 of the shaft holds the shaft in working position.

Rotation of the shaft 58 is thus transmitted to the turret 37 which continually rotates and carries the arms 31 with it. During each rotation of the turret each arm is carried from 45 can receiving position into can discharging position and thence back again to can receiving position thus completing the cycle. It is while an arm is passing between the can receiving and the can discharge positions that the can is carried over the table 23 and held in its turret arm pocket 32 by a curved guide rail 65 (Fig. 1) bolted to the table.

When approaching the discharge position, the can 25 engages an inner guide rail 66 which is 55 spaced from the rail 65 being also mounted upon the table 23. The rail 66 now acts as a stripper and as the can is brought against a curved surface of the guide rail 66 it is moved out of the pocket of the arm and is then brought to any 60 suitable place of deposit. It will be observed that there are no abrupt angles or corners in this path of travel.

It is during the time that a can 25 is received 65 within an arm pocket 32 until it is stripped from the pocket by the guide rail 66 that retardation takes place. This is done by a backing up of the pocket end of the arm while the bodily advance, of the arm with the turret, continues. 70 This will now be described.

Retardation of the outer end of the arm is accomplished by pivotal or rocking movement on its depending shank 35. To effect this pivotal action each arm 31 carries a pin 67 on which 75 is rotatably mounted a cam roller 68 which

traverses a cam groove 69 formed in the lower face of a cam 71 keyed to the reduced end 48 of the shaft 43.

The cam 71 is held in stationary position on the shaft through the medium of a key 72 which extends into the bracket 49 (Fig. 2). The shouleder part of the shaft is also drawn up against the cam, holding it against the bracket. A washer 73 and lock bolt 74 threadedly engaging the upper end of the shaft is used for this clamping purpose.

As an arm 31 approaches the can receiving position its outer can pocket end is held in forward position on its turret mounting. The rotation of the turret is such as to insure uniform 15 lineal movement of the pockets 24, 32 at this time. The arm 31 now receives the can 25 in its pocket 32.

There is no pivotal movement or at least only slight pivotal movement of the arm until the can 20 is taken out of the turret pocket 24 and moved along the guide rail 65. From the position indicated by the letter A (Fig. 1) until the can leaves the turret arm the cam groove 69 operating on the cam roller 68 pivots the arm 31 backward 25 so that the can is retrograded in its passage along the rail 65. At station B (Fig. 1) the can comes against the rail 66 and the moving arm 31 then sweeps it from its pocket 32. As soon as the arm has delivered the can it is pivoted in the opposite direction during the following 180° or more of turret rotation and is brought again in position to receive another can at the proper time.

It is thought that the invention and many 35 of its attendant advantages will be understood from the foregoing description, and it will be apparent that various changes may be made in the form, construction and arrangement of the parts without departing from the spirit and scope of the invention or sacrificing all of its material 40 advantages, the form hereinbefore described being merely a preferred embodiment thereof.

I claim:

1. A can feeding mechanism for receiving cans from a rapidly moving can carrier, comprising 45 a movable member adapted to move adjacent said carrier and at substantially the same speed of travel, can receiving pockets carried by said movable member for receiving the cans from said carrier and for retarding their travel by moving back relative to said member as the cans are advanced, and means for discharging said retarded cans from said feeding mechanism.

2. A can feeding mechanism for receiving cans from a rapidly moving can carrier, comprising 55 a rotatable member having can receiving pockets movable adjacent said carrier and moving at substantially the same speed of travel so that a can is received therein, and means for retrograding the speed of said can receiving pockets with respect to the speed of rotation of said rotatable member to retard the travel of a said can while it is in said can receiving pocket.

3. A can feeding mechanism for receiving cans from a rapidly moving can carrier, comprising a 65 rotatable member having can receiving pockets movable adjacent said carrier and moving at substantially the same speed of travel so that a can is received therein, means operating on said 70 can receiving pockets for altering their speed relative to the speed of rotation of said rotatable member while a can is within a said pocket to retard the travel of said can therein, means for discharging said retarded can, and means for 75

accelerating the travel of said can receiving pocket while empty to again present it in proper can receiving position for a subsequent can.

4. A can feeding mechanism for receiving cans from a rapidly moving can carrier, comprising a turret rotatably mounted adjacent said can carrier, arms mounted on said turret and having can receiving pockets into which the rapidly moving cans are transferred from said carrier, and means operating on said arms while being carried by said turret to move them back relative to the turret and while turret, arm and can are advancing together for uniformly retarding the travel of said arm pockets and the cans carried thereby so that the cans are discharged from said turret at a slower travel than their travel in said carrier.

5. A can feeding mechanism for receiving cans from a rapidly moving can carrier, comprising a turret rotatably mounted adjacent said can

carrier, arms pivotally mounted on said turret and having can receiving pockets, means for transferring cans from said carrier into said arms pockets, and a stationary cam mounted on the axis of said turret and operating on said arms for pivoting them on their turret mountings and retrograding their travel while a can is in a feed arm pocket to retard the movement of said cans while in said arm pockets.

6. A can feeding mechanism for receiving cans from a rapidly moving can carrier, comprising in combination movable pockets for receiving the cans from the rapidly moving carrier and in the spaced relation given them in the carrier, said pockets uniformly slowing the advancement of the cans to bring them into closer spaced relation while moving with said pockets, and means for discharging said cans from said movable members.
